FLOODLIGHT

Harry E. Rutledge, Pittsburgh, Pa.

Application November 24, 1950, Serial No. 13,116

Term of patent 14 years

(Cl. D48—20)

To all whom it may concern:

Be it known that I, Harry E. Rutledge, a citizen of the United States, residing at Pittsburgh, in the county of Allegheny and State of Pennsylvania, have invented a new, original, and ornamental Design for a Floodlight, of which the following is a specification, reference being had to the accompanying drawing, forming a part hereof.

Fig. 1 is a front perspective view of a floodlight showing my new design;

Fig. 2 is a top plan view thereof; and

Fig. 3 is a side elevational view.

I claim:

The ornamental design for a floodlight, as shown.

HARRY E. RUTLEDGE.
